US0D1074721S

(12) **United States Design Patent** (10) Patent No.: **US D1,074,721 S**
(45) Date of Patent: **** May 13, 2025**

(54) **DISPLAY SCREEN WITH GRAPHICAL USER INTERFACE**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **29/984,658**

(22) Filed: **Jan. 15, 2025**

Related U.S. Application Data

(62) Division of application No. 35/520,976, filed on May 18, 2023 (U.S. filing date under 35 U.S.C. 384), and having an international filing date of May 18, 2023.

CLAIM

The ornamental design for a display screen with graphical user interface, as shown and described.

DESCRIPTION

The sole FIGURE is a front view of the display screen with graphical user interface showing my design.

The long-dash broken lines forming the periphery illustrate the display screen and form no part of the claimed design. The remaining broken lines show portions of the graphical user interface that form no part of the claimed design.
